BOILER

James C. Hobbs, Painesville, Ohio

**Application January 13, 1928, Serial No. 246,411
Renewed August 23, 1933**

13 Claims. (Cl. 122—298)

This invention relates to a water tube boiler in which some of the tubes are arranged above the boiler furnace to form a slag screen. The invention will be understood from the following description in connection with the accompanying drawings, in which Fig. 1 is a vertical section through an illustrative embodiment of the invention; Fig. 2 is a section along the line 2—2 of Fig. 1, and Fig. 3 is a section similar to Fig. 2 showing a modification.

15 In the drawings, reference character 1 indicates the front wall of a furnace that is provided with a bridge wall 2 at the rear. One of the side walls is shown at 3 in Figs. 2 and 3. The furnace is provided with a stoker 4, and a water tube boiler of a well-known type with inclined water tubes is illustrated as being located above the furnace. The boiler comprises a plurality of longitudinal drums 5 that are supported by means of straps 6 from I-beams 7. The drums are connected to the upper ends of downtake headers 8 and uptake headers 9 which are, in turn, connected by a bank of parallel inclined tubes 10. The lower ends of the headers 8 and 9 are connected by means of nipples 11 and 12 to the upper ends of headers 13 and 14 which are, in turn, connected by a bank of parallel inclined tubes 15. The downtake and uptake headers are shown as vertically extending, and the tubes connecting these headers and which are disposed above the furnace are shown as being disposed in rows spaced apart vertically and with the tubes in any one row disposed in a horizontally inclined plane, except as hereinafter noted. For the sake of convenience of expression and to define a relation to some datum, the various parts will be herein-after referred to thus, by reference to the vertical and horizontal, although the angles which the headers and tubes make with respect to the vertical and horizontal are not essential parts of the invention.

30 The lowermost row of the tubes 15 has the ends of selected tubes, shown in Fig. 2 as being alternate tubes, bent so that the major portions 16 of these selected tubes lie some distance below and parallel to the other tubes in the row. The lower ends of these selected tubes are bent at two points 17 and 18 to provide a portion 19 that is substantially horizontal, so that the tubes will drain into the headers 13, and the upper ends of the tubes are bent as indicated at 20, so that the ends of the bent tubes enter their headers along the same horizontal lines as the ends of the remaining straight tubes in the row.

35 The above construction provides an arrange-

ment in which the tubes in one row, for example the lowermost row in the bank, have their end portions disposed in a common horizontally inclined plane and in which the selected tubes have the major portions thereof disposed out of that plane and in another plane parallel thereto, these major portions being connected to their end portions by means of reverse bends. In the embodiment shown in Fig. 1, the plane occupied by the portions 16 of the selected tubes is one which passes below the lowermost ends of the headers, as will be plainly seen from an inspection of Fig. 1. It will likewise be noted that since the portion 19 of a selected tube is horizontal, and since the same selected tube is in each instance connected to the downtake header at the lowest point of the tube, there can be no downward flow of any fluid passing from the downtake header to the uptake header.

Nipples 21 connect the lower ends of the headers 13 to the mud drum 22 and baffles 23 and 24 direct the hot products of combustion from the furnace across the banks of tubes 10 and 15 into the outlet 25.

In the modification shown in Fig. 3, the lower headers 14' are made straight along their lower portions instead of sinuous as in Fig. 2, and some of the rows of tubes 15' have the tubes in the rows spaced apart horizontally twice as far as the corresponding tubes in rows 15. The ends of the bottom row of tubes all enter the headers along the same horizontal lines and alternate tubes 16' are bent downwardly in the same way as above described in connection with the tubes in Fig. 25 30

2. In this modification, some of the tubes 16' are omitted, the third tube of each group of three being omitted to provide triangularly shaped spaces for radiant heat to enter and strike tubes higher in the bank than is possible with the usual construction. 40

The way in which the tubes of the lowermost row are spaced in Fig. 3 would apply to the tube arrangement shown in Fig. 2 by omitting certain of the tubes in the lowermost row of the tube bank shown in Fig. 2. 45

By bending the selected tubes as above described, from one row into an adjoining row wider spaces are left between tubes immediately above the furnace, thus forming a slag screen, so that the trouble due to the spaces between the tubes being bridged by slag collecting upon the tubes is obviated and the opening of the passage to the next row of tubes above permits the absorption of more radiant heat. Also the opening of the 55

entrance to the first row of tubes permits the velocity of the gases entering to be decreased. When some of the tubes are omitted, as shown in Fig. 3, the radiant heat is enabled to strike tubes at a higher level in the tube bank and in some cases to strike a given tube from two directions through wider lanes than is possible with the ordinary arrangement. When the radiant heat strikes tubes at a higher level, the amount of radiant heat that is thrown back is intercepted in part and absorbed by some of the tubes which come nearer the furnace.

This arrangement is particularly effective where slag adheres to the under sides of the tubes in the lowermost row. When this occurs in the ordinary arrangement the slag becomes heated and reflects radiant heat back into the furnace and at the same time prevents the full absorption of the radiant heat by the lowermost tubes by forming a heat resisting coating on the tubes. With the lowermost tubes bent and spaced in the way described, the slag which accumulates on the lowermost line of tubes will have a lesser effect in throwing the heat back into the furnace than with the ordinary arrangement of tube bank where the tubes are not so spaced.

Likewise, the invention is one which can be readily applied either to a boiler already in place or to a boiler which is being installed new. For example, if it is desired to provide a slag screen for a boiler which is already in place, without materially changing existing structure, it will be seen that my invention provides a ready way of doing so. If selected tubes in a certain row are to be displaced from the plane of that row, then the old holes in the headers which received the tubes replaced by the selected tubes, and which holes of course are in that same plane, may be used to receive the end portions of the selected tubes. Therefore, very little change in existing structure is necessary. At the same time, the invention may be readily used with new installations.

While I have shown the invention as embodied in a specific form, it is to be understood that various changes in details may be made without departing from the scope of the invention, as defined by the appended claims.

I claim:

1. In a water tube boiler, uptake and downtake headers, a bank of inclined tubes connected to said headers and extending across the upper portion of the boiler furnace, the alternate tubes of the lowermost rows being bent at their ends so as to make the main portion of the alternate tubes in the lowermost row come below the remainder of the tubes in the lowermost row, some of said alternate bent tubes being omitted.

2. In a water tube boiler, uptake and downtake headers, a bank of inclined tubes connected to said headers and extending across the upper portion of the boiler furnace, alternate tubes in the lowermost row being bent and the main portions thereof lying below the other tubes of that row, and each third tube of said alternate tubes being omitted.

3. In a water tube boiler, vertically extending uptake and downtake headers connected by tubes extending above a furnace, the lowermost tubes being connected to said headers closely adjacent the lower ends of the headers, end portions of all of said lowermost tubes being arranged in a row and the major portions of selected ones of said lowermost tubes being arranged in another lower row and being joined to their end portions by reverse bends, said lower row being disposed in a plane extending below the lower end of the headers to which said headers to which said end portions are connected.

4. In a water tube boiler, vertically extending uptake and downtake headers connected by tubes extending above a furnace, the lowermost tubes being connected to said headers closely adjacent the lower ends of the headers, end portions of all of said lowermost tubes being arranged in a row and the major portions of selected ones of said lowermost tubes being arranged in another lower row and being joined to their end portions by reverse bends, said lower row being disposed in a plane extending below the lower end of the headers to which said headers to which said end portions are connected.

5. In a water tube boiler, vertically extending uptake and downtake headers connected by tubes extending above a furnace, the lowermost tubes being connected to said headers closely adjacent the lower ends of the headers, the end portions of all of said lowermost tubes at both ends of the tubes being arranged in a row and the major portions of selected ones of said lowermost tubes being arranged in another lower row and being joined to their end portions by reverse bends, said lower row being disposed in a plane extending below the lower end of the headers to which said headers to which said end portions are connected and being parallel to the plane of said first-named row.

6. In a water tube boiler, vertically extending uptake and downtake headers connected by tubes extending above a furnace, the lowermost tubes being connected to said headers closely adjacent the lower ends of the headers, the end portions of all of said lowermost tubes at both ends of the tubes being arranged in a row and the major portions of selected ones of said lowermost tubes being arranged in another lower row and being joined to their end portions by reverse bends, said lower row being disposed in a plane extending below the lower end of the headers to which said end portions are connected.

7. In a water tube boiler, uptake and downtake headers connected by tubes, said tubes extending upwardly from the downtake header to the uptake header, a slag screen comprising certain of said tubes having the opposite end portions thereof disposed in a horizontally inclined plane, the major part of the length of a tube intermediate its end portions being displaced out of said plane and joined to said end portions by reverse bends, the bends being so formed and arranged that the lowest points in the bent tubes are located at their connections to the downtake headers.

8. In a water tube boiler, uptake and downtake headers connected by tubes, said tubes extending upwardly from the downtake header to the uptake header, a slag screen comprising certain of said tubes having the opposite end portions thereof disposed in a horizontally inclined plane, the major part of the length of a tube intermediate its end portions being displaced out of said plane but substantially parallel thereto and joined to said end portions by reverse bends, the bends being so formed as to substantially avoid any downward flow of a fluid passing through a tube from the downtake header to the uptake header.

9. In a water tube boiler, uptake and downtake headers connected by tubes, said tubes extending upwardly from the downtake header to the uptake header, a slag screen comprising certain of said tubes having end portions at one end thereof disposed in a horizontally inclined plane, the

major part of the length of a tube intermediate its opposite end portions being displaced out of said plane and joined to the end portion in said plane by a reverse bend, said bend being so formed as to substantially avoid any downward flow of a fluid passing through a tube from the downtake header to the uptake header.

10. In a water tube boiler, uptake and downtake headers connected by tubes, said tubes extending upwardly from the downtake header to the uptake header, a slag screen comprising certain of said tubes having the opposite end portions thereof disposed in a horizontally inclined plane, the major part of the length of a tube intermediate its end portions being disposed below said plane and joined to said end portions by reverse bends, the bends being so formed as to substantially avoid any downward flow of a fluid passing through a tube from the downtake header to the uptake header.

15. In a water tube boiler, uptake and downtake headers connected by tubes, said tubes extending upwardly from the downtake header to the uptake header, a slag screen comprising certain of said tubes having the opposite end portions thereof disposed in a horizontally inclined plane, the major part of the length of a tube intermediate its end portions being disposed below said plane but substantially parallel thereto and joined to said end portions by reverse bends, the bends being so formed and arranged that the lowest points in the bent tubes are located at their connection to the downtake headers.

12. In a water tube boiler, uptake and downtake headers connected by tubes, said tubes extending upwardly from the downtake header to the uptake header, a slag screen comprising certain of said tubes having end portions at one end thereof disposed in a horizontally inclined plane, the major part of the length of a tube intermediate its opposite end portions being disposed below said plane and joined to the end portions in said plane by a reverse bend, said bend being so formed and arranged that the lowest point in said tube is located at its connection to the downtake header.

13. In a water tube boiler, uptake and downtake headers connected by tubes, said tubes extending upwardly from the downtake header to the uptake header and arranged in horizontally extending rows forming a bank of tubes, the majority of said rows being spaced apart vertically and entering holes in said headers, which holes are spaced apart horizontally, one of said rows being formed by some only of the tubes in an adjoining row displaced for the major parts of their lengths from said adjoining row but having their end portions entered in holes in said adjoining row and connected to said major parts by reverse bends, whereby the horizontal spacing of the tubes in the rows from which and to which said tubes are displaced is increased without changing the arrangement of holes in said headers.

JAMES C. HOBBS.
